UNITED STATES PATENT OFFICE.

DOUGLAS H. ELEY AND THOMAS H. RYAN, OF NORFOLK, VIRGINIA, ASSIGNORS TO
THE EMORY RUBBER SOLE CO., INC., OF NORFOLK, VIRGINIA, A CORPORATION OF
VIRGINIA.

DESIGN FOR A RUBBER PAD FOR SHOE-SOLES.

56,345.

Specification for Design.

Patented Oct. 5, 1920.

Application filed January 15, 1920. Serial No. 351,621. Term of patent 7 years.

To all whom it may concern:

Be it known that we, DOUGLAS H. ELEY and THOMAS H. RYAN, citizens of the United States of America, residing in the city of Norfolk, county of Norfolk, State of Virginia, have invented a new, original, and ornamental Design for a Rubber Pad for Shoe-Soles, of which the following is a specification, reference being had to the accompanying drawings, forming part thereof.

Figure 1 is a plan view in perspective, and

Fig. 2 is a longitudinal view in perspective, showing our improved design.

We claim:—

The ornamental design for a rubber pad for shoe soles as shown.

DOUGLAS H. ELEY.
THOMAS H. RYAN.
